DESIGN FOR A FRUIT JUICE EXTRACTOR

Joseph M. Majewski, Jr., Kansas City, Mo., assignor to Foster L. Talge, Kansas City, Mo., doing business as Rival Manufacturing Company

Application July 17, 1936, Serial No. 63,889

Term of patent 7 years

To all whom it may concern:

Be it known, that I, Joseph M. Majewski, Jr., residing at Kansas City, in the county of Jackson and State of Missouri, have invented a new, original, and ornamental Design for a Fruit Juice Extractor, of which the following is a specification, reference being had to the accompanying drawing, forming part thereof, in which

I claim:

The ornamental design for a fruit juice extractor substantially as shown.

In testimony whereof, I affix my signature.

JOSEPH M. MAJEWSKI, JR.
